UNITED STATES PATENT OFFICE.

WILLIAM A. LORENZ AND JOSEPH MERRITT, OF HARTFORD, CONNECTICUT, ASSIGNEES,
BY DIRECT AND MESNE ASSIGNMENTS, OF ONE-HALF TO BEECH-NUT PACKING COMPANY,
OF CANAJOHARIE, NEW YORK, A CORPORATION OF NEW YORK, AND ONE-FOURTH
TO SAID LORENZ AND ONE-FOURTH TO WILLIAM H. HONISS, OF HARTFORD,
CONNECTICUT.

HERMETIC-SEALING APPARATUS.

1,125,138.

Specification of Letters Patent. Patented Jan. 19, 1915.

Application filed May 6, 1907. Serial No. 372,064.

To all whom it may concern:

Be it known that we, WILLIAM A. LORENZ and JOSEPH MERRITT, citizens of the United States, and residents of Hartford, in the county of Hartford and State of Connecticut, have invented certain new and useful Improvements in Hermetic-Sealing Apparatus, of which the following is a full, clear, and exact specification.

10 This invention relates to improvements in processes and apparatus for hermetically sealing jars and similar receptacles, and particularly relates to a vacuum sealing apparatus comprising a plurality of sealing apparatus arranged in multiple which may be used in alternation or succession, whereby the air may be exhausted from the jars in one chamber while a second chamber is being emptied of sealed jars, and refilled 20 with another lot of jars to be sealed.

Figure 1 is a plan view of a duplex or two-chamber sealing apparatus, showing their common door closed against the right hand chamber and the air being exhausted 25 therefrom. Fig. 2 is a front view and Fig. 3 an end view of the apparatus of Fig. 1. Fig. 4 is a front view, showing the door before the left hand chamber and the air being exhausted from this chamber. The upper part is shown in section on line 4-4 of Fig. 1. Figs. 5, 6, 7 and 8 are end views 30 in section on the line 5-5 of Fig. 2, showing the controller valve in its four positions. Fig. 9 is an end view showing the valve in its fourth position, admitting air to the presser chamber and jar chamber. Fig. 10 is a fragmentary end view showing the door in its retracted position to clear the faces of the chambers. Fig. 11 is a side 35 view, in reduced scale of a pump for exhausting the air from the chambers. Figs. 12 and 13 are front views, in section on the line 12-13 of Fig. 9, showing the switch valve in its two positions.

40 The duplex or multiple jar chambers 20 and 21 are inclosed on all sides except the front, by the shell or frame work 22 which rests upon the leg or stand 23. The open fronts of the jar chambers are closed alternately for the sealing operations within, by the door 24 faced with the gasket 25 and supported by means of the links 29 and 30

in the rolling carriage 38, on which the door swings laterally toward and away from the open face of either jar chamber, being so 55 moved by means of the screw 35 engaging a hub of the carriage 38, and having the lever 36. This lateral movement of the door is to insure that the gasket clears the faces of the chambers while being moved back 60 and forth from one chamber to the other. In order thus to carry the door from the face of one chamber to the face of the other chamber, it is supported upon a carriage provided with rollers 39 and 40 which 65 roll upon the track 42 supported by the bracket 43, and with the roller 60, which rolls in a guideway 61 of a bracket 43, and guides the rearward side of the carriage, holding that rearward side against up or 70 down movement. In order to prevent the carriage 38 from lifting at its forward side, as for example, while drawing the door back from its seat against the chambers, it is provided with rolls 58 and 59 which bear 75 upon the under surface of the track 40 (Fig. 3). The carriage, being thus mounted on rollers, is easily pushed by hand from the face of one chamber to the face of the other chamber, being shown in its extreme 80 positions in Figs. 2 and 4. Means are provided for preventing the door from being seated elsewhere than at the extreme ends of its movement, directly before the respective chambers. As herein shown this means 85 consists of a projecting ledge 89 in front of each chamber, the door being cut away at 88 so as to clear the ledge at each of its proper seating positions, as shown in Fig. 2. At any other position the door would 90 collide with the ledge, thus obstructing the movement of the door in such a way as to call the operator's attention to it.

In order to stop the movement of the rolling carriages 38 at each end of its stroke and 95 without appreciable shock or jar, stop plugs 63 and 64 of rubber or similar material are employed. As herein shown, these plugs are preferably appurtenant to the carriage and strike against the brackets 66 and 67 at 100 the respective ends of the track 42, stopping the carriage at the proper position before each chamber. This traveling movement of the door carriage from one chamber to the

other is utilized to direct or transfer the pneumatic connections from one chamber to the other by operating a switch valve or valves situated in the exhaust pipe 100 which leads from the sealing apparatus to any suitable air exhausting apparatus, such, for example, as the rotary pump 46 shown in Fig. 11, it being understood, however, that any other suitable apparatus may be employed. Each of the sealing chambers is separately connected with and disconnected from the air exhausting apparatus, the communication being cut off from one chamber when communication is made with the other chamber. Communication is thus made between the main pipe 100 and the two conduits 95 and 96, which serve the right and left hand sealing chambers, respectively. In the present instance the control of the communication between the main pipe 100 and these two conduits is by means of the switch valve 56 situated at their junction. As best shown in Figs. 4, 12 and 13, the air communication between these conduits 95 and 96 and the respective chambers is further controlled by means of a controlling valve 91 to be hereinafter described, the function of the switch valve 56 being only to put the port 97 into communication with the required conduit 95 or 96, subject to the further control of the controlling valve 91. Thus the pneumatic connections of the respective chambers are automatically adjusted in conjunction with the door movements, without requiring attention from the operator, who therefore has to operate but one valve in the same manner each time, for the different chambers, with no possibility of operating upon any but the closed chamber. This avoids the possible waste of time and of motive power, which would result from operating the pneumatic devices in connection with an open sealing chamber, through inadvertence or otherwise.

The switch valve 56 is mounted in a suitable casing, preferably attached to the lower side of the casing 93 of the valve 91, and is provided with a tapering plug 55 having a transverse channel or passage 97, the lower end of which is widened so as to be in communication with the main pipe 100, at all times, while the upper end of the port 97 is by the turning of the plug adapted to register separately with the conduits 95 and 96 when their respective sealing chambers are to be put in operation. This valve is turned automatically to the two positions shown in Figs. 12 and 13 by means of the door carriage. The valve plug 55 is provided with a depending lever 53 connecting with a link 50 which extends horizontally behind the door carriage and is supported at its other end in any convenient way, as by means of the swinging arm 51 pivoted in the brackets 52. The connecting link 50 is provided with

adjustable collars 47 and 48 and the carriage 38 is provided with an arm or extension 45 which collides with these collars, the latter being set at the proper positions to insure the working of the switch valve 56 at the right time and to the required extent. When moved toward the right to the position shown in Fig. 2, the arm 45 collides with the collar 47, thereby moving the valve to the position shown in Fig. 12. In moving to the left to the position shown in Fig. 4, the arm 45 strikes the collar 48 thus moving the valve to the position shown in Fig. 13, in each case diverting the exhaust communication to the conduit for the chamber in front of which the door stands at that time.

The jars J to be sealed are supported in the chambers 20 and 21 in any convenient way, being herein shown as resting upon a base or tray 82, which may be provided with a handle 83 for convenience in withdrawing and replacing the bases in the chambers. Different bases may be provided suited to the height and size of the jars to be sealed.

Any desired form of sealing mechanism may be employed in the chambers to assist in the sealing operation. In the present instance is shown a form of sealing apparatus which, after the desired vacuum is obtained, utilizes the returning atmospheric pressure to press the jar caps G firmly and squarely down upon their closure seats before admitting the air pressure to or around the jars themselves, thereby insuring the complete sealing of the jars while still *in vacuo*.

The top plate 73 of the shell or framework 22 contains two presser chambers 70 and 71 located above the right and left jar chambers 20 and 21, respectively, each jar chamber being hermetically separated from its pressure chamber by the lower wall of the plate 73. The presser cylinders 75, equaling in number the jars to be sealed in the respective chambers, are secured to the under side of the top plate 73, the upper end of each cylinder opening into its presser chamber as best shown in Fig. 4. Each of these cylinders is provided with a presser 77 situated immediately above the jar cap to be sealed; and these pressers are provided with suitable pistons within the cylinder, operated by the atmospheric pressure, which is admitted to the presser chambers 70 and 71 while the jars in the chamber below are *in vacuo*. In the present instance two pistons arranged in tandem relation are employed, the presser 77 serving as one piston secured to the piston rod 78, while the upper piston 76 is secured to the upper end of the rod. The cylinders 75 are each divided by a horizontal partition 79 into two chambers one for each of the tandem pistons.

A passage 81 leads from the upper chamber to the lower chamber to enable the air

pressure to take effect upon both pistons simultaneously. A spring 80 is also preferably employed of a tension sufficient to overcome the weight and friction of the pistons and hold them in their upper position shown in Fig. 4. The employment of these multiple pistons thus arranged in tandem relation enables them to be made of moderate sizes so as to arrange the jars in close order, 5 while also enabling a powerful pressure to be applied to the jar caps for the sealing down operation. In the embodiment herein shown the pistons are approximately the size of the jar caps themselves and the atmospheric pressure acting upon the two tandem pistons produces an initial sealing pressure upon the cap approximately twice that which is subsequently exerted by the atmospheric pressure to maintain the cap in 15 place, no mechanical clamps, or springs, or other devices being employed, in this class of jar to hold the covers in place.

In order to properly control the flow of air to and from the jar chambers and their 20 respective sealing chambers, four separate branch conduits are provided, one for each chamber, connecting them with the controlling valve 91. The two branches 101 and 102 in the channel bracket 94 connect with 25 the presser chambers 70 and 71 respectively (Fig. 4) while the jar chambers 20 and 21 are connected with the valve by means of the two branches 110 and 111 respectively.

The controlling valve 91 is provided with 30 a tapering plug 92, having two independent sets or systems of ports and passages 108 and 109 controlling the exhaustion from and readmission of air to the two sets of chambers. The set of these ports and passages 35 which are for use in connection with the right hand chambers 20 and 70 is shown in Figs. 5-8. This set, operative when the switch valve plug 55 is in the position shown in Fig. 2 is in the plane of the conduit 95, 40 branch 101 and pipe 110, while the other and similar set of ports and passages is in the plane of the branch 102, pipe 111 and conduit 96 and is operative upon the left hand chambers 21 and 71 when the switch 45 valve plug 55 is in the position shown in Fig. 4, opening the conduit 96 to the exhaust pipe 100.

In the plane of each set or section 108 and 109 of ports and passages is an air inlet 50 port 99 (Figs. 5-8) through which air is readmitted, first to the presser chamber (Fig. 7) and then also to the jar chamber (Fig. 8). The two sets or systems of ports and passages 108 and 109 are alike, hence only 55 one set is fully shown in the drawings. In Figs. 5 to 8 inclusive this set of ports 108 is shown in the four positions to which it is moved by turning the valve plug 92.

In the first position, shown in Fig. 5, the 60 air is being exhausted only from the pres-

sure chamber 70 for the purpose of lifting any of the pressers, which may not have been returned to their upper positions by their springs 80 after the previous operation. Therefore in this position the inlet 70 65 99 and the branch pipe 110 are closed, while the branch 101 is open to the exhaust passage 95 to a sufficient extent to lift the pressers.

In the second position, shown in Fig. 6, 70 which is the regular exhausting position of the valve, the inlet port 99 is still closed, while the branch 102 and pipe 110 are opened to the exhaust passage 95, thus exhausting the air from the jar chamber 20 75 80 and its presser chamber 70.

In the third position, shown in Fig. 7, the conduit 95 and the branch 110 are closed so as to hold the vacuum in the jar chamber 20 and air is being admitted through the inlet 85 99 and the branch 102 to the presser chamber 70.

In the fourth position, shown in Fig. 8, the conduit 95 is still closed; but air is now admitted through the branch 110 to the jar 90 chamber 20, as well as to the presser chamber 70 through the conduit 102.

The controlling valve plug 92 is moved from one position to another by means of the lever 113 secured to the stem 114 of the 95 plug, and having a handle 115 on its outer end. A latch 116 is pivoted on the lever 113 by the bolt 117 and carries on its outer end a handle 118. The inner end of the latch forms a pawl 120 which rides upon the indexing plate 121, forming a part of the 100 valve casing 93. The circumferential edge of the plate 121 is provided with four shoulders, 1, 2, 3, 4, indicative of the four positions just described, which shoulders when 105 engaged by the pawl, stop the turning movement of the plug at the respective positions.

A spring 122 keeps the pawl in engagement with the plate except when drawn back by the handle 118. In this way the 110 valve is easily operated by the lever 113 to turn it from one position to another almost instantly, and with the certainty of arresting the movement when the valve reaches the position desired, and also to visibly indicate its position at all times by the numerals on the shoulders corresponding with the respective positions of the valve.

The operation of this apparatus is as follows:—The filled jars J, having their 115 caps G and gaskets loosely placed in position, are set in place in a jar tray 82, beginning, for example, with the chamber 20, the 4-way valve 91, meanwhile being in its first position (Fig. 5). The door carriage is 120 then rolled in front of the chamber 20, as shown in Fig. 2, the latter portion of its movement serving to turn the switch valve plug 55 to the position shown in Figs. 2 and 12, thus placing the main exhaust pipe 125 130

100 in communication with the conduit 95 for the right hand jar and presser chambers. The door 24 is then closed against the face of the chamber by means of the screw 35 and the controlling valve plug 92 is turned to the second position (Fig. 6) thereby placing the jar chamber 20 and its presser chamber 70 in communication with the exhaust, through the conduits 110 and 101, respectively. While this exhaustion of the right hand chamber is being continued the left hand jar chamber 21 is emptied of the jars previously sealed, and a new set of jars placed in position for the succeeding 15 operation.

A suitable vacuum gage should be provided to enable the operator to observe the degree of vacuum obtained. As soon as that degree is reached, the operator turns 20 the controlling valve plug 92 to its third position shown in Fig. 7, thereby cutting out communication through the conduit 95 with the exhaust pump, and admitting atmospheric pressure through the inlet 99 and 25 branch 101 to the presser chamber 70, while still closing the branch 110 leading to the jar chamber 20, and thus preserving the vacuum therein. The action of the readmitted air to the presser chamber 70 and 30 behind the pistons 76 and 77 is almost instantaneous, pressing down the caps firmly upon the jars. The controlling valve plug 92 is then turned to its fourth position (Fig. 8) thus admitting the atmospheric pressure 35 also through the branch 110 to the jar chamber 20, thus holding the jar caps firmly down, while at the same time balancing the pressure in the presser chamber 70 so that the jar pressers 77 are released and are 40 raised by their springs to their upper positions, as shown in Figs. 2 and 4. The door is then loosened and retracted from the face of the chamber 20 and the door carriage is rolled to the position shown in Fig. 4, carrying 45 the door in front of the other chamber 21 which has already been loaded with jars ready for the sealing operation. This movement of the door carriage operates through the rod 50 to swing the switch valve 50 plug 55 to the position shown in Figs. 4 and 13, thus shutting off the exhaust pipe 100 from communication with the conduit 95 and placing it in communication with the conduit 96 leading to the series of ports 109 55 of the valve plug 92, appurtenant to the left hand chambers. The door is then closed and the controlling valve plug 92 is moved as before to its first, second and third positions, as already described, the right hand 60 jar chamber being meanwhile emptied of its sealed jars, and filled with a new lot of jars to be sealed. Thus the operation continues alternately upon the two chambers.

Various modifications and transpositions 65 of the mechanism herein shown may be

made while keeping within the general spirit and scope of the invention.

In ways which will suggest themselves to those skilled in this art, the various devices and groups of devices herein shown may be 70 modified or differently arranged to adapt them to various conditions of service.

The multiple presser pistons shown and described herein are shown, described, and claimed in U. S. Patent #886,663, granted 75 Sepetember 24, 1907 to William A. Lorenz.

We claim as our invention:—

1. The combination, in sealing apparatus, of a plurality of chambers, a door adapted to hermetically seal any of said chambers, a carriage on which the door is mounted for transportation from one sealing position to another and means appurtenant to the carriage for closing the door in each position to seal any of the chambers. 85

2. The combination, in sealing apparatus, of a plurality of chambers, a door adapted to hermetically close any of said chambers, a carriage on which the door is mounted, ways for guiding the carriage with the door from 90 one sealing position to another and means appurtenant to the carriage for closing the door in each position to seal the respective chambers. 95

3. The combination, in sealing apparatus, of a plurality of sealing chambers arranged in multiple, a door adapted to hermetically close any of said chambers, a carriage on which the door is mounted, ways for guiding the carriage when conveying the door 100 from one sealing position to another and mechanism transported by the carriage for closing the door against the respective chambers. 105

4. The combination, in sealing apparatus, of a plurality of sealing chambers, a door adapted to hermetically close any of said chambers, door mechanism for supporting and guiding the door from one sealing position to another, including means for clamp- 110 ing the door to close any of the chambers. 115

5. The combination, in sealing apparatus, of a plurality of sealing chambers, a door adapted to hermetically close any of said chambers, door mechanism for conveying 115 the door from one chamber to another, including means for clamping the door against the chambers, and means for registering the door in proper position before each chamber, prior to clamping it thereto. 120

6. The combination, in sealing apparatus, of a plurality of sealing chambers, pneumatic connections for the respective chambers, a door adapted to seal any of the said chambers, means for moving the door into 125 sealing relation to the respective chambers, and means controlled by the position of the door for operating the said pneumatic connections.

7. The combination, in sealing apparatus, 130

5 of a plurality of sealing chambers, pneumatic connections for the said chambers, a door adapted to seal any of said chambers, a carriage adapted to transport the door from one sealing position to the other relative to the chambers, and means controlled by the position of the door for operating the said pneumatic connections.

8. The combination, in sealing apparatus, 10 of a plurality of sealing chambers arranged side by side with their open sealing faces facing approximately in the same direction, a door adapted to hermetically close any of said chambers, a carriage upon which the door is mounted for transportation from the front of one chamber to the front of the other chamber, and means for closing the said door against any chamber.

9. The combination, in sealing apparatus, 20 of a plurality of sealing chambers, a door for hermetically closing any of said chambers, means for conveying the door from one sealing position to another, air exhausting means connected with the chambers and 25 means operably connected with the door conveying means to provide air exhausting communication to the sealing chamber to which the door is moved.

10. The combination, in hermetic sealing 30 apparatus, of a plurality of sealing chambers, a door for sealing any of said chambers, means for guiding the door from one sealing position to another, means for exhausting air from the chambers, and means 35 operably connected with the door guiding means for automatically disconnecting communication between the air exhausting means and the chamber from which the door is moved away.

40 11. The combination, in exhausting and sealing apparatus, of a plurality of sealing chambers, a door for hermetically closing any of said chambers, means for guiding the door into sealing relation to any of said 45 chambers, air exhausting means, and means operably connected with the door guiding means for automatically directing communication from the air exhausting means to the chamber to which the door is moved.

50 12. The combination with hermetic sealing apparatus, of a plurality of sealing chambers arranged in multiple, a door for hermetically closing any of said chambers, means for guiding the door while being 55 moved into sealing relation to any chamber, means for exhausting the air from each chamber separately, and means operable by the movements of the door for automatically providing exhaust communication to the 60 chamber to which the door is moved.

13. The combination, in sealing apparatus, of a plurality of sealing chambers, air exhausting means provided with conduits for each of said chambers, a valve having 65 a plurality of air ports controlling the con-

duits for the different chambers, a door for sealing any of said chambers, means for guiding the door while being moved into sealing relation to any chamber, and means operably connected with the door guiding 70 means for operating the said valve to place the air exhausting means in communication with the conduit for the chamber to which the door is moved.

14. The combination, with sealing apparatus, 75 of a plurality of sealing chambers, a door for hermetically sealing any of said chambers, means for guiding the door from one sealing position to another, air exhausting means provided with air conduits for the 80 respective chambers, a switch valve controlling the air communication to the respective conduits, and means operably connected with the door guiding means for operating the switch valve.

85 15. The combination, in hermetic sealing apparatus, of a plurality of sealing chambers arranged in multiple, air conduits for the respective chambers, and a valve having multiple sets of ports and passages 90 separately controlling the respective air conduits.

16. The combination, in hermetic sealing apparatus, of a plurality of sealing chambers, air exhausting means having branch 95 air conduits for the respective chambers, a switch valve having an air passage to provide air communication to any of the said conduits, and a controller valve controlling the flow of the air through and from the said 100 conduits.

17. The combination, in sealing apparatus, 105 of a plurality of sealing chambers, each having a jar chamber and a presser chamber, air exhausting means having conduits for the respective sealing chambers, a switch valve provided with an air passage directing the air communication through any of said conduits, branches connecting each of said conduits with the respective pressure and 110 jar chambers, and a valve controlling air communication from the conduits through their respective branches.

18. The combination, in sealing apparatus, 115 of a plurality of sealing chambers, each comprising a jar chamber and a presser chamber, air exhausting means having conduits for the respective sealing chambers, branches connecting each of said conduits with the respective jar and presser chambers, a switch valve having an air passage 120 to provide air communication to any of said conduits, and a controller valve for directing the communication from the conduits to their respective branches, the said 125 controller valve being also provided with means closing the said communication and readmitting atmospheric pressure to the presser and jar chambers.

19. The combination, in sealing appara- 130

tus, of a plurality of sealing chambers, each comprising a jar chamber and a presser chamber, air exhausting means having conduits for the respective sealing chambers, a 5 switch valve having an air passage to direct air communication to any of the said conduits, branches connecting each conduit with the presser and jar chambers of its associated sealing chamber, and a controlling 10 valve controlling communication between each conduit and its branches, the controlling valve being also provided with means closing the said conduit and readmitting atmospheric pressure separately to the jar and 15 presser chambers.

20. The combination, in hermetic sealing apparatus, of a plurality of sealing chambers, air exhausting means provided with conduits for the respective chambers, a controller valve controlling the said conduits having a separate series of ports and passages for each chamber, and provided also with means for closing the said conduits to the air exhausting means and readmitting atmospheric pressure to the sealing chambers. 25

21. The combination, in hermetic sealing apparatus, of a plurality of sealing chambers provided with compartments, air exhausting means provided with conduits for 30 the respective chambers, branches from the said conduits to different compartments of their respective sealing chambers, and a controller valve having a separate set of ports and passages for each conduit controlling communication between each conduit and its 35 branches.

22. The combination, in hermetic sealing apparatus, of a plurality of sealing chambers provided with compartments, air exhausting means provided with conduits for the respective chambers, branches from the said conduits to different compartments of their respective sealing chambers, and a controller valve having a separate set of ports 40 and passages for each conduit, controlling communication between each conduit and its branches, the valves being also provided with means for shutting off air exhaust connections from the conduits and readmitting atmospheric pressure to the respective 45 branches of the conduits.

23. The combination, in sealing apparatus, of a plurality of sealing chambers, a door for hermetically closing any of said 55 chambers, mechanism for guiding the door from one sealing position to another, air exhausting means connected with the chambers, a switch valve controlling the said connection to the said chambers, and means 60 connecting the door guiding mechanism with the said valve, whereby the movement of the door mechanism to a particular chamber operates to direct the air exhausting communication to that chamber.

24. The combination, in sealing appara-

tus, of a plurality of sealing chambers, a door for sealing any of said chambers, door mechanism for guiding the door from one sealing position to another, means for exhausting air, having separate conduits for 70 the chambers, a switch valve for the said conduits, and means connecting the said valve with the said door mechanism whereby the movements of the latter to a particular chamber provides air exhausting 75 communication to the conduit for that chamber.

25. The combination, in hermetic sealing apparatus, of a plurality of sealing chambers, a door for sealing any of said chambers, door mechanism for guiding the door from one sealing position to another, air exhausting means having conduits for the respective chambers, a switch valve controlling the air exhausting communication to 80 the respective conduits, a connecting rod for said valve, and adjustable dogs on said rod disposed in the pathway of the door mechanism, whereby the latter in moving from one chamber to another operates through the 85 valve to provide the air exhausting communication to the conduit for the latter chamber.

26. The combination, in hermetic sealing apparatus, of multiple sealing chambers, air 90 exhausting means having branch conduits leading to the respective chambers, means for switching the air exhausting connection to either branch, and a controlling valve having multiple sets of ports and passages 100 controlling the respective branch conduits.

27. Hermetic sealing apparatus, including in combination a plurality of sealing chambers, provided with air exhaust connections, means for opening and closing the 105 said chambers, and means operable with the chamber closing means for opening air exhaust connection to a closed chamber and closing it from an open chamber.

28. Hermetic sealing apparatus, including in combination a plurality of sealing chambers provided with air exhaust connections, a door for closing any of the said chambers separately, and means operable with the door for opening the air exhaust connection 110 of the chamber closed by the door, and closing the air exhaust connection of the open chamber.

29. Hermetic sealing apparatus, including in combination two sealing chambers, door 120 mechanism for separately and alternately closing the two chambers, and means operable by the movement of the door mechanism from one chamber to the other, for closing the air exhaust connection of the 125 chamber from which the door mechanism is moving away, and opening the air exhaust connections of the chamber to which the door is moving.

30. The combination, in hermetic sealing 130

apparatus, of a plurality of sealing chambers arranged in multiple, air exhausting means having branch conduits leading to the respective chambers, and a controlling valve having multiple sets of ports and passages controlling the respective branch conduits, and having also an inlet for admitting atmospheric pressure through its ports and passages to the respective branch conduits.

10 31. Multiple sealing apparatus, comprising

ing sealing chambers, a plurality of branch conduits for each sealing chamber, and a controlling valve having a set of ports and passages separately controlling the branch conduits of the respective sealing chambers. 15
